UNITED STATES PATENT OFFICE

HENRY TYLER, OF CINCINNATI, OHIO

DESIGN FOR A MOTOR VEHICLE

Application filed March 10, 1932. Serial No. 43,146. Term of patent 14 years.

To all whom it may concern:

Be it known that I, HENRY TYLER, a citizen of the United States, residing at Cincinnati, in the county of Hamilton and State of Ohio, have invented a new, original, and ornamental Design for a Motor Vehicle, of which the following is a specification, reference being had to the accompanying drawings, forming part thereof.

Fig. 1 is a perspective view of a vehicle showing my new design;

Fig. 2 is a side elevation thereof;

Fig. 3 is a front view of said vehicle; and

Fig. 4 is a rear view thereof.

I claim:

The ornamental design for a motor vehicle, substantially as shown.

HENRY TYLER.
